ASSEMBLY AND FASTENER THEREFOR

William D. Stockdale, Arlington Heights, Ill., assignor to Illinois Tool Works, Chicago, Ill., a corporation of Illinois

Application January 27, 1956, Serial No. 561,794

5 Claims. (Cl. 16—42)

The present invention relates to a structure including a tubular member, an end member and a device for securing said members together, and more particularly to a novel fastening device for such a structure.

Articles of furniture have long been made with tubular metal legs having caps or feet secured to their lower ends or other tubular frame or arm members having their ends closed by caps. The caps or feet are formed from various materials including plastics, and various fastening devices have been suggested for securing such caps or feet to the tubular members. Heretofore proposed fastening devices for the purpose contemplated herein have not always been entirely satisfactory since certain of the devices are at least partially disposed so that they mar the appearance of the structure, and other fastening devices frequently enable the feet or cap members to become loose, particularly when these members are formed from a plastic material which is subject to cold flow after periods of use.

An important object of the present invention is to provide a novel structure of the above described type which includes a fastening device entirely concealed within the tubular member and cap or foot member and which is capable of securely and permanently retaining the members in assembled relationship.

A further object of the present invention is to provide a novel one-piece sheet material device of relatively simple and economical construction, which device is adapted to secure a cap or closure member to the end of a tubular member securely and with the device hidden from view.

A further object of the present invention is to provide a novel one-piece sheet material fastening device of the above described type which may be easily and securely applied to both the tubular member and the cap or closure member so as to facilitate assembly of these members.

Other objects and advantages of the present invention will become apparent from the following description and the accompanying drawing wherein:

Fig. 1 is a fragmentary elevational view showing a structure incorporating the principles of the present invention;

Fig. 2 is an enlarged sectional view taken along line 2—2 in Fig. 1;

Fig. 3 is a perspective view showing a novel fastening device embodying the principles of the present invention;

Fig. 4 is a sectional view taken along line 4—4 in Fig. 2; and

Fig. 5 is an enlarged elevational view showing the novel fastening device of this invention.

Referring now more specifically to the drawing wherein like parts are designated by the same numerals throughout the various figures, a structure 10 incorporating the features of the present invention is shown in Figs. 1, 2 and 4. This structure includes a tubular member 12 which, in the embodiment shown, has a circular transverse cross section, but it will be understood that the tubular member may have any desired cross sectional

shape. It is contemplated that the tubular member 12 may be a leg of an article of furniture or the like, and a foot member 14 is applied to the lower end of the tubular member. However, it should also be understood, 5 that the tubular member 12 may be utilized to provide frame or arm members for various articles of furniture, handle members for appliances such as vacuum sweepers or for any other desired purpose, and in such instances the member 14 provides a cap or closure for the end 10 of the tubular member. The foot or closure member 14 is securely and permanently fastened to the tubular member by means of a one-piece fastener member 16 which is preferably formed from resilient sheet metal. As shown in the drawings, the fastener member is formed 15 and applied so that it is completely enclosed within the tubular and end or closure members so that it will not detract from the external appearance of the structure.

The foot or cap member 14 is preferably formed from a plastic material but also may be formed from other 20 suitable materials such as wood and metal. This member is provided with a tubular inner end portion 18 having the same cross sectional shape as the tubular member 12 and adapted to fit snugly within the end of the tubular member 12. A radially extending annular shoulder 20 25 is provided on the member 14 for engaging the terminal end of the tubular member 12 and thereby positively limiting entry of the foot or cap into the tubular member. An outer end portion 22 of the foot or cap member is preferably closed or substantially closed and may be 30 provided with a substantially semispherical shape as shown or any other desired shape.

The fastening device 16 is preferably formed from a strip of sheet material of substantially uniform width throughout its length and includes a central or body 35 section 24 which may initially be substantially flat and disposed perpendicularly to the longitudinal axis of the device as shown in Figs. 3 and 5. Leg portions 26 and 28 extend from opposite ends of the section 24, which leg portions respectively include relatively short sections 40 30 and 32 diverging from integral junctions with the section 24, and converging sections 34 and 36. The sections 30 and 32 are inclined laterally and generally axially inwardly from the section 24 at relatively large angles such, for example, as about 65°. Prongs 38 and 45 40 are struck from the sections 30 and 32 respectively and are inclined laterally and axially inwardly from integral junctions with opposite ends of section 24 at relatively small angles, such, for example, as about 30°. The reversely extending or converging leg sections 34 50 and 36 are disposed at angles of about 40° with respect to the plane of the section 24, and additional prongs 42 and 44 are struck from the sections 30 and 32 respectively and extend from integral junctions with the sections 34 and 36 at angles of about 20° with respect to the plane 55 of the section 24. It will be appreciated that the specific angles mentioned herein are given by way of example only, and that the specific illustrated configuration of the legs 26 and 28 is subject to modification.

The fastening device 16 is easily and securely applied 60 to the foot or cap member 14 merely by pressing the end portion of the fastener including the sections 24, 30 and 32 and the prongs 38 and 40 into the tubular section 18 of the foot or cap member. As shown in Fig. 2 the normal distance between the terminal ends of the prongs 38 and 40 is greater than the transverse internal dimension or diameter of the foot or cap member so that the section 24 and prongs will be flexed upon insertion into the member 14 whereby the prongs will aggressively engage the member 14. It should be noted that the section 65 24 is substantially flexed upon assembly with the member 14 so that in the event that this member is formed from plastic and cold flow occurs, the section 24 will 70

still function to maintain the prongs in aggressive engagement with the member 14. Thus the foot or cap member 14 cannot become loose or accidentally disassembled from the fastening device even after long periods of use.

During assembly of the fastening device with the cap or foot member 14, the prongs 42 and 44 engage the inner terminal end of the portion 18 so as to limit movement of the fastening device into the foot member. Preferably the fastening device is pressed into the foot member until the prongs 42 and 44 are deflected slightly away from the section 24 as shown in Fig. 2. As a result the member 14 is resiliently clamped between prongs 38—42 and 40—44 so as further to insure aggressive engagement of the prongs 38 and 40 with the member 14.

The ends of the leg portions 26 and 28 of the fastening device disposed outwardly from the section 24 respectively merge with curved sections 46 and 48 which in turn respectively merge with reversely extending sections 50 and 52. Thus, the outer ends of the sections 50 and 52 are disposed in opposing relationship with respect to the prongs 38 and 40 for engaging the inner wall of the tubular member 12. The curved portions 46 and 48 are initially spaced apart as shown in Figs. 3 and 5, and the outer ends of the sections 50 and 52 are initially spaced apart a distance greater than the internal transverse dimension or diameter of the tubular member 12. Thus the fastening device which is first applied to the foot or cap member may be easily and securely applied to the tubular member 12 merely by pressing the sections 50 and 52 into the tubular member so that the end edges or corners of the sections 50 and 52 bite into the tubular member as shown best in Figs. 2 and 4. The fastening device is constructed and proportioned with respect to the tubular member 12 so that when the device is inserted within the tubular member, the leg portions 26 and 28 are collapsed until the curved sections 46 and 48 abut each other and the sections 50 and 52 are flexed so as aggressively to engage the tubular member. The relatively broad sheet material curved sections 46 and 48 cannot slip past each other when the fastening device is applied to the tubular member so that each leg portion and curved section serves to back-up the other leg portion and curved section whereby aggressive engagement of the sections 50 and 52 with the tubular member is insured. As shown in the drawings the terminal ends of the sections 50 and 52 may be notched as at 54 and 56 respectively so as to provide a plurality of relatively narrow prongs 58—60 and 62—64. These prongs provide improved engagement with a tubular member having flat interior surfaces, not shown, but for a circular tubular member these prongs may be omitted, if desired. Furthermore the end edges of the sections 50 and 52 could be shaped so as to conform with any flat or arcuate interior surface of the tubular member, and these edges, in certain instances, may be continuous and in other instances they may be interrupted so as to provide teeth or prongs.

While the preferred embodiments have been shown and described herein, it is obvious that many structural details may be changed without departing from the spirit and scope of the appended claims.

The invention is claimed as follows:

1. A one-piece resilient sheet material fastening device for connecting first and second tubular members comprising a section disposed transversely to a longitudinal axis of said device, means projecting from an end of said section for engaging an interior surface of the first tubular member and restraining axial shifting of said device with respect to said first tubular member toward the second tubular member, a pair of resilient leg means respectively extending from opposite ends of said section generally axially of said device, elements respectively connected to and extending laterally of said leg means

for engaging an interior surface of said second tubular member and restraining shifting of said device with respect to said second tubular member toward said first tubular member, and a pair of normally spaced apart

means including portions of said leg means adjacent said elements extending toward each other over said section into adjacent relationship, said pair of means being shifted toward each other and into abutting relationship when said elements are engaged with the interior surface of said second tubular member for firmly supporting said elements in engagement with said second tubular member.

2. A resilient sheet material fastening device, as defined in claim 1 which includes means on said leg means for engaging said first tubular member for limiting axial movement of said device into said first tubular member and for urging said means extending from said section into engagement with said first tubular member.

3. A resilient sheet material fastening device comprising a one-piece strip including a central section of predetermined length disposed transversely with respect to a longitudinal axis of said device, a pair of prong means extending generally oppositely with respect to each other from said section adjacent opposite ends of said section and inclined laterally from one side of said section facing

axially in one direction and at an angle to said axis for engaging an interior surface of a first member, a pair of leg sections respectively extending generally axially from opposite ends of said section in said one direction for entry into a second member, and a pair of means re-

spectively extending laterally from said leg sections and inclined with respect to said axis in a direction opposite to one said direction and extending generally oppositely with respect to each other for engaging an interior surface of said second member, said pair of means having

terminal ends engageable with said last named surface spaced apart a distance substantially greater than said length of said transverse section, said leg sections including intermediate portions spaced apart a distance substantially less than said length of said transverse section, which portions abut each other to limit collapsing of the leg sections toward each other when said terminal ends are engaged with said interior surface of said second member.

4. A one-piece resilient sheet material fastening device comprising a first section at one end of the device traversing a longitudinal axis of the device, a pair of opposed leg portions extending from said first section generally toward an end of the device opposite from said one end, generally oppositely projecting elements extending

from said first section adjacent opposite ends of said first section for engaging an interior surface of a first member, generally oppositely and laterally projecting elements extending from said leg sections adjacent said opposite end of the device for engaging an interior sur-

face of a second member, and means struck from intermediate portions of said leg sections and projecting laterally outwardly at a location between said first and second mentioned elements for engaging said first member for limiting entry of said first section into said first member.

5. A structure of the type described comprising a tubular member, an end member including an outer terminal end portion disposed outwardly of one end of said tubular member, said end member including a tubular portion extending inwardly into said tubular member from said

one end of the tubular member, said end member including annular radially outwardly projecting shoulder means engaging said one end of a tubular member and limiting movement of said tubular portion to said tubular member, an inner end of said tubular portion providing an annular abutment within said tubular member, and a one-piece resilient sheet material fastening device disposed within and securely retaining said members in assembled relationship, said fastening device including a resilient flexed section disposed within said tubular portion outwardly of said inner end of the tubular portion

in a direction toward said outer terminal end of said end member, said flexed section traversing said tubular portion and having prong portions extending oppositely with respect to each other aggressively engaging opposite interior surface portions of said tubular portion and inclined at an acute angle with respect to a longitudinal axis of said members toward said inner end of the tubular portion, a pair of resiliently flexed elements respectively extending from opposite ends of said section, said elements being oppositely disposed with respect to each other and abutting each other centrally of said tubular member and respectively including end portions located within said tubular member axially inwardly of said tubular portion and engaging opposite interior surface portions of said tubular member and inclined at an acute

5

angle with respect to said axis toward said inner end of said tubular portion, and a pair of resilient flexed prongs respectively struck from intermediate portions of said elements and extending oppositely from each other and engaging said annular abutment for limiting entry of said section into said tubular portion and for urging said prong portions into aggressive engagement with said tubular portion.
